UNITED STATES PATENT OFFICE.

JESSE W. D. DAVIS, OF PHOENIX, ARIZONA.

COTTON-DISTRIBUTER.

1,316,282.

Specification of Letters Patent. Patented Sept. 16, 1919.

Application filed July 17, 1918. Serial No. 245,346.

To all whom it may concern:

Be it known that I, JESSE W. D. DAVIS, a citizen of the United States, residing at Phoenix, in the county of Maricopa and State of Arizona, have invented certain new and useful Improvements in Cotton - Distributors; and I do hereby declare the following to be a full, clear, and exact description of the invention, such as will enable others skilled in the art to which it appertains to make and use the same.

This invention relates to a cotton distributor, and particularly to the push board ordinarily used in a roller gin for use upon long staple cotton.

The invention has for an object to provide a novel and improved construction of reciprocating push board having mounted thereon a toothed cotton distributor movable independently of the board and preferably laterally to the travel of the board.

A further object of the invention is to provide a push board having at its outer edge a toothed cotton distributor bar slidably mounted thereon together with means for reciprocating this distributor independently of the movement of the board and laterally thereto.

Other and further objects and advantages of the invention will be hereinafter set forth and the novel features thereof defined by the appended claims.

In the drawings.

Figure 1 is a central vertical section showing the application of the invention.

Fig. 2 is a top plan of the push board and distributor with parts of the former broken away, and

Fig. 3 is a detail plan showing a modified form of means for actuating the distributor.

Like numerals refer to like parts in the several figures of the drawing.

The numeral 10 designates the casing of a cotton gin which may be of any desired size or configuration and is provided with suitable tracks of ways 11 in which the usual type of push board 12 is adapted to reciprocate. This board may be actuated by any desired means, for instance; the pitman rods 13 pivoted thereto at 14 and also pivoted at 15 to a crank arm 16 carried by a driving shaft 17. This shaft may be oscillated by any mechanical means, for instance: crank 18 thereon from which an actuating rod 19 extends to a source of power. This

push board 12 reciprocates toward and from the usual gin knives 20 disposed adjacent the gin roller 21 as indicated in Fig. 1 but may coöperate with any desired construction of cotton gin mechanism.

The cotton distributor bar 22 may be mounted upon the push board 12 in any preferred manner, a desirable form thereof being herein shown in which the distributor bar is disposed in a slot 23 formed in the outer free edge of the board and adapted to move therein laterally of the direction of travel of the board. For the purpose of retaining the distributor 22 and guiding its movements it is provided with elongated slots 24 through which pins 25 removably secured to the board extend. The distributor is also provided with teeth or needles 26 to operate upon and loosen any massed cotton which may lie in the path of the gin knives.

The distributor may be actuated in any desired manner, a preferred form being shown herein, in which one end of the distributor bar is curved as at 27 and adapted to ride upon the inclined face 28 of cam block 29. This moves the bar in one direction and it is adapted to be restored in the returning movement of the push board by means of the coiled spring 30 disposed in the recess 31 of the board and extending between the end wall of said recess and a lug 32 carried by the distributor bar as shown in Fig. 2.

A modified form of the actuating means for the distributor bar is shown in Fig. 3 wherein the bar 36 is of the same general construction as shown in Fig. 2, but is provided with curved faces 33 at opposite ends. One of these faces travels upon a cam block 34 similar to block 28, for moving the bar in one direction and the bar is restored by means of an oppositely disposed cam face 35 upon the other side of the gin casing so as to secure a positive movement in both directions.

In operation of the invention a push board is reciprocated toward and from the gin knives in the usual manner and during said travel the distributor pins or needles are reciprocated laterally of the board in opposite direction so as to keep the seed cotton from banking in front of the knives and scatter it so that the cotton seed may be passed through the gin and relieve the bank.

ing of the feed against the knives. The seed cotton which falls from the upper part of the gin stand is liable to bank up in front of the push board unless means be provided to 5 distribute and separate this mass. Such bulked seed cotton forms a compact body which is liable to spring or break the gin knives. It will be seen that the push board provided with this distributor provides two 10 movements one forcing the cotton toward the gin knives and the other distributing it over the area thereof and thus relieves the congestion.

While this invention has been shown as 15 applied to a particular type of cotton gin and means disclosed for operating the parts still the invention is not confined to the details thereof, but embraces the novel construction of push board and distributor as 20 defined by the patent claims.

Having described my invention and set forth its merits I claim and desire to secure by Letters Patent:—

1. In the cotton distributer, a gin mechanism, a push board mounted to reciprocate toward and from said mechanism, a distributor mounted upon said push board to move therewith and also laterally of its travel, and means for actuating said distributor due to its movement with the push-board.

2. In the cotton distributer, a gin mechanism, a push board mounted to reciprocate toward and from said mechanism, a distributor mounted upon said push board to move laterally of its travel, a cam for actuating said distributor in one direction, and means for restoring said distributor.

3. In the cotton distributer, a gin mechanism, a push board mounted to reciprocate toward and from said mechanism and provided with a slot in its free edge, a toothed distributor bar mounted to slide in said slot to move with said board, and means relatively to which said bar is movable with said board for reciprocating said bar.

4. In the cotton distributer, a gin mechanism, a push board mounted to reciprocate toward and from said mechanism and provided with a slot in its free edge, a toothed distributor bar mounted to slide in said slot,

a cam face adapted to contact with one end of said bar, and means to restore said bar.

5. In the cotton distributer, a gin mechanism, a push board mounted to reciprocate 55 toward and from said mechanism and provided with a slotted free edge, a toothed distributor bar mounted in said slot and provided with elongated slots therein, guide pins carried by the board and extended 60 through said elongated slots, an inclined cam face carried by the gin casing and adapted to contact with one end of said bar, and means for restoring said bar.

6. In the cotton distributer, a gin mechanism, a push board mounted to reciprocate 65 toward and from said mechanism and provided with a slotted free edge, a toothed distributor bar mounted in said slot and provided with elongated slots therein, guide 70 pins carried by the front and extended through said elongated slots, an inclined cam face carried by the gin casing and adapted to contact with one end of said bar, a lug carried by said bar and extending into 75 a recess within said board, and a restoring spring disposed in said recess to bear against said lug.

7. In the cotton distributer, a gin mechanism, a push board mounted to reciprocate 80 toward and from said mechanism, a distributor, mounted upon said board and movable therewith and also independent thereof, and means for moving said distributor by its travel with said board.

8. In the cotton distributer, a gin mechanism, a push board mounted to reciprocate toward and from said mechanism, a distributor mounted upon said board and movable therewith and also independent thereof, and means relatively to which said distributor is movable with said board for moving said distributor laterally to the path of travel of said board and during the movement of the board.

In testimony whereof I have signed my name to this specification in the presence of two subscribing witnesses.

JESSE W. D. DAVIS.
